(57) **CLAIM**

The ornamental design for a tabletop microphone, as shown and described.

DESCRIPTION

FIG. 1 is a perspective view of a tabletop microphone showing my new design;

FIG. 2 is a top plan view thereof;

FIG. 3 is a side elevational view of one side thereof;

FIG. 4 is a side elevational view of the opposite side thereof;

FIG. 5 is a rear elevational view thereof; and,

FIG. 6 is a front elevational view thereof.

The broken lines in the drawings depict portions of the tabletop microphone that form no part of the claimed design.
